DESIGN FOR FABRIC OR SIMILAR MATERIAL

Harry J. Aaronson, Brooklyn, N. Y.

Application May 25, 1934, Serial No. 51,923

Term of patent 3½ years

To all whom it may concern:

Be it known that I, HARRY J. AARONSON, a citizen of the United States, residing in Brooklyn, New York, in the county of Kings and State of New York, have invented a new, original, and ornamental Design for a Fabric or Similar Material, of which the following is a specification, reference being had to the accompanying drawing, forming part thereof.

The single figure is a plan view of the fabric or similar material showing my new design.

The dominant feature of the present invention resides in the base fabric having discs of contrasting material stitched thereto as indicated by the dotted lines. The ornamented fabric thus produced is particularly adapted for use in shoe uppers, ladies' handbags, etc.

I claim:

The ornamental design for a fabric or similar material, as shown and described.

HARRY J. AARONSON.
